UNITED STATES PATENT OFFICE.

JOSEF NOWOTNY, OF VIENNA, AUSTRIA.

SAFETY LATCH.

Application filed June 1, 1927, Serial No. 195,671, and in Austria March 15, 1927.

My present invention relates generally to latches, and has particular reference to an improved safety latch for employment with suitcases, bags, handbags, and the like.

5 It is well known that the latches heretofore employed are frequently of a character which snap open of their own accord, resulting in considerable annoyance. It is one object of my present invention to provide a latch wherein the inadvertent opening thereof is greatly minimized.

10 It is another object of my invention to provide a latch which is, nevertheless, of a character which is simple to close and 15 equally simple to open despite the security with which the latch remains closed unless properly manipulated.

Another object is to provide a latch which 20 may be closed in the usual and customary manner, i. e., by simply applying and pressing one element against another element, interengagement of the elements being thereby effected.

25 A further object lies in providing a latch which is so constructed that opening of the latch cannot be effected by a mere mutual retraction by said interengaging elements, but can be effected in a simple and expeditious manner by moving said elements relatively to each other in a direction different from such retractive direction.

30 In general, it is an object to provide a latch which is of simple construction and which is of neat appearance and compact, 35 so that the shape of the bag with which the latch is employed is not impaired.

For the attainment of the foregoing objects and such other objects as may herein-after appear or be pointed out, I have constructed two embodiments of my invention 40 and illustrated in the accompanying drawings in which—

Figure 1 is a plan view of the bottom or engaging portion of the latch with the cover plate thereof removed to disclose the interior; the parts being shown in the positions which they assume when the latch is closed;

45 Figure 2 is a view similar to Figure 1 showing a slight modification and showing the parts in the positions they assume when the latch is being opened;

50 Figure 3 is a cross-sectional view taken substantially along the line A—B of Figure 1 and showing the complementary ele-

ment of the latch in poised position ready 55 for engagement with the portion illustrated in Figure 1; and

Figure 4 is a view similar to Figure 3 taken substantially along the line C—D of Figure 2.

60 The bottom or engagement portion of the latch comprises the casing 1 provided with a substantially flat cover plate e. An engagement element a is mounted in the casing 1 in such a manner as to be pivotable and also movable in a radial direction with respect to said pivot. A spring b, mounted in the casing 1, tends automatically and continuously to hold the element a in the position shown in Figure 1, i. e., with the free 65 end of the element a furthest from the pivot point. A closing member c, also pivotally mounted in the casing 1, is continuously acted upon by a spring d and is thus constrained continuously to press against 70 the side of the element a, thereby normally holding the element a in the position shown in Figure 1.

75 It is obvious that the element a is pivotally movable around the pivot point thereof (at the upper end of Figure 1) against the action of the spring d; and it is also clear that the slot adjacent the pivoted end of the element a permits the latter to be moved longitudinally with respect to itself against 80 the action of the spring b.

85 A slot f is provided in the cover plate e and is arranged to overlie the free end or tip of the element a when the latter is in the normal position of Figure 1. The slot f 90 is arranged along a tangent with respect to the arcuate movement of the tip of the element a. The closing member c underlies the major portion of the slot f under normal 95 conditions.

The complementary catch element of the latch is designated by the reference numeral 2 and is adapted to be associated in a suitable manner with the complementary portion of the bag. In the form of Figures 1 and 3 the catch element 2 is provided with the apertured element g, and in the form of Figures 2 and 4 such apertured element is supplanted by a knob element h. The catch element, whether apertured or knob-shaped, 100 is adapted to be pushed through the slot f into the casing 1 and into engagement with the free end or tip of the complementary 105 element 2.

engagement element *a*. For this purpose, the engagement element *a* of Figures 1 and 3 has its tip beveled or inclined. In the form of Figures 2 and 4 the knob *h* is 5 beveled instead of the forward tip of the engagement element *a*.

It will be obvious that when the catch element is pushed down against the free tip of the engagement element *a*, these two elements will automatically interengage in a 10 well known manner, and the normal closure of the latch is thus effected. When it is desired to reopen the latch, however, a mere retractile movement of the catch element will be insufficient and in this way inadvertent opening of the latch is prevented.

To open the latch, the portion 2 must be deliberately and purposely moved in a side- 20 ward direction so that the catch element will travel along the tangential line defined by the slot *f*. When this movement is effected, the engagement element *a* is drawn with it for a certain distance but presently will find 25 itself released. This is due to the fact that the catch element is constrained to move along the tangential direction defined by the slot *f*, while the engagement element *a* is constrained by its pivotal mounting to move its tip along the arcuate path indicated 30 in Figure 2. In this way the tip moves sideways and then backward and becomes released. During this arcuate movement, the closing member *c* will have been rotated 35 into the position of Figure 2 but as soon as release is effected and the portion 2 is withdrawn from the slot *f*, the parts will all resume the normal positions shown in Figure 1 under the actions of the springs *b* and *d*.

40 It will be obvious that changes in the details herein described and illustrated for the purpose of explaining the nature of my invention may be made by those skilled in the art without departing from the spirit and 45 scope of the invention as expressed in the appended claims. It is therefore intended that these details be interpreted as illustrative, and not in a limiting sense.

Having thus described my invention and 50 illustrated its use, what I claim as new and desire to secure by Letters Patent is—

55 1. In a latch of the character described, a catch element, a complementary engagement element so mounted as to be pivotable and also movable in a radial direction with respect to said pivot, means for causing inter-engagement of said elements by a movement of the engagement element in said radial direction, and means for preventing 60 separation of said elements except by a pivotal movement of said engagement element.

65 2. In a latch of the character described, a slotted casing, an engagement element pivoted therein, yieldable means for normally holding the free end of said element under

said slot, and said element being so mounted that said free end may be made to yield either radially toward the pivot point or arcuately about said pivot point.

3. In a latch of the character described, 70 a slotted casing, an engagement element pivoted therein, yieldable means for normally holding the free end of said element under said slot, and said element being so mounted that said free end may be made to yield 75 either radially toward the pivot point or arcuately about said pivot point; said yieldable means comprising a spring which is arranged to counteract said radial yielding; and a second spring which is arranged to 80 counteract said arcuate yielding.

4. In a latch of the character described, 85 a slotted casing, an engagement element pivoted therein, yieldable means for normally holding the free end of said element under 90 said slot, and said element being so mounted that said free end may be made to yield either radially toward the pivot point or arcuately about said pivot point; said yieldable means comprising a spring which is arranged to counteract said radial yielding; and a second spring which is arranged to 95 counteract said arcuate yielding; and a pivoted member interposed between said second spring and said engagement element and having a portion which normally underlies said slot.

5. In a latch of the character described, 100 a slotted casing, an engagement element pivoted therein, yieldable means for normally holding the free end of said element under one end of said slot, said element being so mounted that said free end may be made to yield either radially toward the pivot point or arcuately about said pivot point, and said 105 slot being arranged along a tangential direction with respect to said arcuate yielding.

6. In a latch of the character described, 110 a slotted casing, an engagement element pivoted therein, yieldable means for normally holding the free end of said element under said slot, and said element being so mounted that said free end may be made to yield either radially toward the pivot point or arcuately about said pivot point; and a complementary catch element exterior of the 115 casing and so constructed and arranged that application thereof through said slot to said free end will cause the latter to yield momentarily in said radial direction and thereupon engage said catch element in a manner which is inseparable by retractive movement of the catch element out of said slot.

7. In a latch of the character described, 120 a slotted casing, an engagement element 125 therein and so mounted for pivotal movement that the free end of said engagement element normally underlies the slot but will withdraw from beneath the slot when the element is pivoted, a complementary catch 130

element exterior of the casing, said elements being so constructed and arranged with respect to one another that they will automatically inter-engage when the catch element is inserted into said slot and pressed against said free end, and means for preventing re-separation of said elements ex-

cept by movement of said catch element longitudinally of said slot so as to pivot said engagement element to withdraw the free end from beneath the slot. 10

In testimony whereof I affix my signature.

JOSEF NOWOTNY.
